UNITED STATES PATENT OFFICE.

FREDERICK R. SEIDENSTICKER, OF WEST MERIDEN, CONNECTICUT,
ASSIGNOR TO BRADLEY & HUBBARD, OF SAME PLACE.

DESIGN FOR LAMP-BRACKETS.

Specification forming part of Design No. 7,540, dated July 14, 1874; application filed June 3, 1874.
[Term of Patent 7 years.]

CASE D.

To all whom it may concern:

Be it known that I, FREDERICK R. SEIDENSTICKER, of West Meriden, in the county of New Haven and State of Connecticut, have invented a new Design for Lamp-Bracket; and I do hereby declare the following, when taken in connection with the accompanying illustration, to be a full, clear, and exact description of the same, and which said illustration constitutes part of this specification, and represents a perspective view.

This invention relates to a design for bracket for supporting a lamp or other burner; and consists in the peculiar configuration of the arm A, as more fully hereinafter described.

The arm curves upward from the base, then turns short and curved, B, downward to the lamp. At the point where the two curves meet a circular boss, C, is placed, all as shown.

I claim as my invention—

The design for lamp-bracket arm, consisting of the two reverse curves A B with a circular boss, C, at the intersection of the curves, as shown and described.

FREDERICK R. SEIDENSTICKER
